(57) **CLAIM**

The ornamental design for a cable management apparatus, as shown and described.

DESCRIPTION

FIG. 1 is a perspective view of a design for a cable management apparatus;

FIG. 2 is a first side view of the design for the cable management apparatus shown in FIG. 1;

FIG. 3 is a second side view of the design for the cable management apparatus shown in FIG. 1;

FIG. 4 is a front view of the design for the cable management apparatus shown in FIG. 1; and,

FIG. 5 is a back view of the design for the cable management apparatus shown in FIG. 1.

The dashed lines in the drawings which define the bounds of the claimed design form no part thereof.
